SIGNAL LAMP FOR AUTOMOTIVE VEHICLES

Jesse R. Hollins, Brooklyn, N. Y.

Application July 20, 1955, Serial No. 37,044

Term of patent 14 years

(Cl. D48—32)

FIG. 1**FIG. 3****FIG. 2**Fig. 1 is a front elevational view of a signal lamp for automotive vehicles, showing my new design,

Fig. 2 is a bottom perspective view thereof, looking upwards, and

Fig. 3 is a side elevation view thereof.

The dominant features of my design are shown in solid lines.

I claim:

The ornamental design for a signal lamp for automotive vehicles, as shown and described.
